UNITED STATES PATENT OFFICE.

GEORGE J. FRITZ, OF ST. LOUIS, MISSOURI.

DESIGN FOR A DOCTOR-ENGINE.

SPECIFICATION forming part of Design No. 12,954, dated June 6, 1882.

Application filed March 24, 1882. Term of patent 14 years.

To all whom it may concern:

Be it known that I, GEORGE J. FRITZ, a citizen of the United States, residing at the city of St. Louis, in the State of Missouri, have invented a new and original Design for Doctor-Engines, of which the following is a specification, reference being had to the accompanying drawing, forming part thereof.

The drawing is a perspective view.

10 A represents a single base-plate, which supports and to which the parts are attached or secured. It has a projection, B, to which the standards C, supporting the balance-wheel D on the shaft D', are secured.

15 E E represent the pumps, and F the actuating-engine.

G is a pipe connecting the pumps with the pipe H, leading to the boiler.

I represents the walking-beam, supported 20 by standards J J, secured to the base-plate, and inclining toward each other at top. They are connected together by rods K L M.

E' E' represent the rods connecting the pistons of the pumps with the walking-beam, 25 and E² E² represent the guide-rods of the pistons, secured to the tops of the pumps, respectively.

N represents a rod connecting one end of the beam I to the shaft D' by means of an arm or eccentric.

30 T represents a rod connecting the eccentric T' on the shaft D' with the arm U' on the rock-shaft U of the steam-chest F'.

U² represents the piston-rod of the steam-chest.

35 The rock-shaft U is supported by brackets V V secured to the standards J J.

O represents the piston-rod of the engine, connected to one end of the beam I by a rod, P, and to the guide-rods Q Q by a cross-head, 40 R. These guide-rods are secured at their lower ends to the top of the engine and at their upper ends to the standards J J by a strengthening-yoke, S. The pumps and engine are in line, and at their sides are the beam-standards. 45

I claim as my invention—

The design for a doctor-engine, substantially as shown and described.

GEO. J. FRITZ.
